(57) **CLAIM**

(21) Appl. No.: **29/320,794**

The ornamental design for alarm clock amplifier for digital media player, as shown and described.

(22) Filed: **Jul. 3, 2008**

DESCRIPTION

(51) **LOC (9) Cl.** **14-01**

FIG. 1 is a front perspective view of an alarm clock amplifier for digital media player showing my new design;

(52) **U.S. Cl.** **D14/209.1; D14/171**

FIG. 2 is a front view thereof;

(58) **Field of Classification Search** D14/204,

FIG. 3 is a rear view thereof;

D14/209.1, 210–216, 168, 170–172, 188;

FIG. 4 is a right, side view thereof, the opposite side view being a mirror image;

181/143–144, 147–148, 150–153, 157, 198–199;

FIG. 5 is a top view thereof; and,

381/300–303, 306, 332–333, 336, 345, 361–364,

FIG. 6 is a bottom thereof.

381/386–388; D10/1, 2, 15

See application file for complete search history.

Environmental material shown in broken lines form no part
